UNITED STATES PATENT OFFICE

111,451

DESIGN FOR A DOLL

Hale B. Anthony, Rockport, Mass.

Application June 21, 1938, Serial No. 77,972

Term of patent 7 years

To all whom it may concern:

Be it known that I, Hale B. Anthony, a citizen of the United States and resident of Rockport, in the county of Essex and State of Massachusetts, have invented a new, original, and ornamental Design for a Doll, of which the following is a specification, reference being had to the accompanying drawing, forming part thereof, and in which

Fig. 1 is a front view slightly in perspective of a doll showing my new design, and

Fig. 2 is a side view thereof slightly in perspective.

I claim:

The ornamental design for a doll, substantially as shown.

HALE B. ANTHONY.
